UNITED STATES PATENT OFFICE.

MORA M. BARRETT, OF SAN FRANCISCO, CALIFORNIA.

GAS-ENGINE ATTACHMENT.

SPECIFICATION forming part of Letters Patent No. 452,174, dated May 12, 1891.

Application filed January 7, 1891. Serial No. 376,975. (No model.)

To all whom it may concern:

Be it known that I, MORA M. BARRETT, a citizen of the United States, residing at the city and in the county of San Francisco, and 5 State of California, have invented certain new and useful Improvements in Gas-Engine Attachments; and I do hereby declare the following to be a full, clear, and exact description of said invention, such as will enable others skilled in the art to which it most nearly appertains to make, use, and practice the same.

My invention has relation to certain new and useful improvements in electric gas-engine attachments, which consists in the arrangement of parts and details of construction, as will be hereinafter more fully set forth in the drawings, described, and pointed out in the claims.

The object of my invention is to provide 20 for the retention by the electrodes of the proper amount of ductility and flexibility for a greater length of time than when exposed to the direct action of the exploded gas within the engine-cylinder proper, as heretofore, 25 and for this purpose I employ a supplemental or gas chamber outside of the gas-engine cylinder, wherein the electrodes are mounted so as to be within line of the inflowing cool gas, by means of which they are maintained normally in a cool condition.

Referring to the drawings forming a part 30 of this specification, wherein similar letters of reference are used to denote corresponding parts throughout the specification and several views—

Figure 1 is a side elevation of the engine-cylinder, partly broken away, showing supplemental chamber secured thereto; Fig. 2, a top plan view thereof; Fig. 3, an enlarged 40 sectional detail of the supplemental chamber, showing the electrodes; and Fig. 4, a top plan of the chamber with top removed.

The letter A is used to indicate the gas-engine cylinder, and B the piston working 45 therein.

Secured to the engine-cylinder and connected to the interior thereof is the supplemental chamber C, within which works the valve D, which is operated by the inflow of 50 gas through the supply-pipe D'. To the interior of said chamber I secure the electrodes

E E', one to the insulated binding-posts e, the other to wall e' of the chamber. Electrode E' extends forward through the opening c into the cylinder-chamber A', and has 55 its end bent or flanged downward, so as to form the finger e², which is adapted to be engaged by the piston B as it moves upward, and by the upward stroke thereof to be lifted, so as to make contact with electrode E. The 60 electrode E may be hinged to wall e', bolted or otherwise secured thereto. As the piston moves downward the electrical current is broken, inasmuch as the resiliency or gravity of electrode E' causes the separation from electrode E, and the sparks produced by such separation serve to ignite the gas contained within the cylinder.

The operation of the engine and the engine itself is similar, to all extents and purposes, 70 to that shown and described in Letters Patent Nos. 430,506 and 430,505, consequently need not be set forth specifically herein.

By practical working I have discovered that the electrodes when placed outside the combustion-chamber proper retain their proper ductility and flexibility for a much greater length of time than when exposed to the direct action of the exploded gas that is within the engine-cylinder proper, as heretofore. As 80 the inflowing gas passes through the supplemental or valve chamber it serves to maintain the electrodes in a cool condition continually.

Having thus described my invention, what 85 I claim as new, and desire to secure protection in by Letters Patent of the United States, is—

1. The combination, with the gas-engine cylinder, of the supplemental chamber secured 90 thereto, and electrodes secured therein, one of said electrodes being movable and terminating within the engine-cylinder, so as to be operated by the movement of the engine-piston, substantially as and for the purpose set 95 forth.

2. In a gas-engine, the combination of the supplemental chamber, electrodes secured within said chamber outside the engine or combustion cylinder, one of said electrodes being movable and extending within the engine-cylinder, and a downwardly-extending finger 100

formed on the end thereof, said electrode being adapted to be operated by the stroke of the engine-piston, as and for the purpose set forth.

5 3. In a gas-engine, the combination of two flexible electrodes secured outside the combustion-chamber, one of said electrodes extending within the chamber and adapted to be operated by the movement of the pis-

ton, so as to make and break the electrical circuit, as and for the purpose set forth.

In testimony whereof I affix my signature in presence of two witnesses.

MORA M. BARRETT.
